UNITED STATES PATENT OFFICE.

HARRY HIRSCH, OF NEW YORK, N. Y.

DISPENSING CONTAINER.

Application filed December 26, 1922. Serial No. 609,014.

To all whom it may concern:

Be it known that I, HARRY HIRSCH, a citizen of the United States, residing at New York city, in the county of New York and 5 State of New York, have invented new and useful Improvements in Dispensing Containers, of which the following is a specification.

This invention relates to dispensing containers and more particularly to dispensing containers for cereals or the like.

The principal object of the invention is the provision of a device of a character mentioned which is capable of dispensing 15 the contents of the same upon the operation of a manipulating portion, and means for automatically agitating the contents of said container, thereby preventing the contents from clogging and permitting the positive flow of the same through the discharge end of the container.

Another object of the invention is the provision of a plurality of dispensing containers capable of being attached to a support whereby the same may be used as a 25 cereal set for household use.

A further object of the invention resides in the provision of a dispensing container including a novel filling means therefor and 30 a discharge valve, the latter coacting with the former so as to normally hold the container in a dust-proof condition.

A still further object of the invention is the provision of a dispensing container 35 which is simple of construction, cheap to manufacture, easy of operation and the interior of which is accessible for cleaning purposes.

With these and other objects in view, the 40 invention resides in certain novel construction and combination and arrangement of parts, the essential features of which are hereinafter fully described, are particularly pointed out in the appended claims, and are 45 illustrated in the accompanying drawing, in which:—

Figure 1 is a front elevation of a plurality of containers arranged for use as a cereal set.

50 Figure 2 is an enlarged vertical sectional view on the line 2—2 of Figure 1.

Figure 3 is a top plan view of the container, and

55 Figure 4 is a horizontal sectional view on the line 4—4 of Figure 1.

Referring more particularly to the draw-

ings, the numeral 5 designates my improved dispensing container, and in Figure 1 a plurality of the same have been shown in use as a cereal set, supported by means of a 60 clip 6 carried by the container 5, for engagement with a bracket A. The bracket A in turn is secured to a wall or other suitable structure. It is to be understood that the containers may be supported individually as well as in sets. 65

Each of the containers 5 includes a shell member 7 tapering toward the discharge end thereof so as to form a hopper 8. The discharge end is provided with an opening, 70 the walls of which are beveled to form a valve seat 9. The shell member 7 is provided with a rounded top 10, the said top having a portion of the same cut-away so as to form a filling opening 11. At the top 75 of the shell member 7 there is formed a bead 12, and crimped about said bead is a portion 13 of the cover 14. The cover 14 fits snugly over the top 10 of the shell member 7 and is provided with an opening 15 adapted to register with the opening 11 in the top 10 when it is desired to fill the container. The top 10 is further provided with a boss 16 which forms a bearing for the cover 14 thereby allowing the same to be revolved for 80 bringing the openings 11 and 15 into and out of registration. 85

Arranged within and extending above the shell member 7 is a rod 17, the same having a relatively flat portion 18 and a screw portion 19. Formed on the end of the portion 18 is a valve head 20 adapted to co-act with the seat 9. The valve head 20 is stepped as at 21 and it co-acts with the discharge opening for regulating the flow through 90 said opening. The screw portion 19 has its bearing in the boss 16 and is provided with a manipulating portion 22. The manipulating portion 22 may either be bent from the rod 17 or the rod may receive a knob 100 95 should the same be desired.

In operation, the rod 17 is given a turn by means of the manipulating portion 22. This will unseat the valve head 20 from the seat 9 thereby permitting the contents of the container to be discharged. It will be noted that the size of the opening may be regulated by the turning movement given to the core. By reason of the step portion of the valve head it will be further understood 105 that the relatively flat portion 18 of the rod serves to agitate the contents during the 110

turning operation thereof, thereby loosening the contents within the container for permitting the positive flow of its contents.

While there has been shown and described what I consider to be the preferred form of my invention, I do not wish to limit myself to the precise structural details hereby exhibited, that changes, alterations and modifications as come within the claims may be resorted to when desired.

What is claimed as new is:—

1. A dispensing container comprising a shell member, an opening formed in the bottom of said shell member and axially thereof, an agitator extending the length of said shell member and provided with a screw portion for co-action with the walls of a slot formed in the top of said shell member, a manipulative portion at one end of said agitator and extending beyond the top of said shell member, a valve head at the other end of said agitator formed with a plurality of annular shoulders whose diameters increase from top to bottom, whereby movement of said manipulative portion will cause said shoulders to co-act with the walls of said opening for governing the flow of the contents of said shell member through said opening.
2. A dispensing container comprising a shell member whose side walls are curved inwardly toward the bottom and terminate to form a beveled valve seat, an agitator extending the length of said shell member, a manipulative portion formed on one end of said agitator and extending beyond the top

of the shell member, a head formed on the end of said agitator, an annular beveled portion formed on said head for co-action with said beveled valve seat whereby to close the opening defined by said valve seat, a plurality of annular shoulders whose diameters increase from top to bottom, whereby movement of said manipulating portion will cause said shoulders to co-act with the walls of the valve seat for governing the flow of contents from said shoulder.

3. A dispensing container comprising a shell member whose side walls are curved inwardly toward the bottom and terminate to form a beveled valve seat, an agitator extending the length of said shell member, and twisted at a point adjacent one end of the same to form a screw portion for co-action with the walls of an opening formed in the top of said shell member, a manipulating portion formed on one end of said agitator and extending beyond the top of the shell member, a head formed on the end of said agitator, an annular beveled portion formed on said head for co-action with said beveled valve seat whereby to close the opening defined by said valve seat, a plurality of annular shoulders whose diameters increase from top to bottom, whereby movement of said manipulating portion will cause said shoulders to co-act with the walls of the valve seat for governing the flow of contents from said shoulder.

In testimony whereof I have affixed my signature.

HARRY HIRSCH.
